DEASPHALTING AND DEWAXING
HYDROCARBON MIXTURES

Harold C. Myers, Woodbury, N. J., assignor to
Socony-Vacuum Oil Company, Incorporated, a
corporation of New York

No Drawing. Application August 27, 1947,
Serial No. 770,953

12 Claims. (Cl. 196—14.15)

1

The present invention relates to the removal of asphaltic materials from hydrocarbon mixtures followed by the removal of high molecular weight paraffinic materials and, more particularly, to the deasphalting and dewaxing of residua employing a mixture of agents for dewaxing which is also used for deasphalting.

If the general development of the art of deasphalting and dewaxing petroleum fractions may be summarized in a few words, it may be said that petroleum fractions are deasphalting by using liquefied normally gaseous hydrocarbons such as propane as diluents and dewaxed by chilling, employing as diluent a solvent such as propane or a solvent mixture such as benzene and methylethyl ketone. Although these practices have much in their favor and provide satisfactory results from a technological viewpoint, they possess economic disadvantages. The use of propane as a diluent for dewaxing propane deasphalting oil requires more refrigeration and produces oilier waxes than when employing benzene-ketone mixtures. When the latter mixture is utilized for dewaxing propane deasphalting oil, distillation is required between the deasphalting and dewaxing operations, necessitating investments in stills and tankage and the expenses incurred in operating this equipment.

It has now been discovered that one diluent can be used for both purposes. The novel diluent is a mixture of propane and an organic carbonate which as a deasphalting agent is capable of providing a yield of superior quality oil equivalent to that obtained when the same propane alone is used. When the novel diluent is used as a dewaxing mixture it produces a wax with a lower oil content at a lower dewaxing temperature pour point differential than when propane is used alone. Accordingly, it is an object of the present invention to provide a novel mixture for use in deasphalting and dewaxing hydrocarbon mixtures. It is another object of the present invention to provide a deasphalting mixture capable of producing substantially the same quantity of lighter colored, lower carbon residue deasphalting oils than produced by conventional deasphalting which deasphalting mixture is used to dewax the deasphalting hydrocarbon mixtures. It is a further object of the present invention to provide a deasphalting mixture which produces a larger quantity of higher viscosity, lighter colored deasphalting oil of comparable carbon residue than is produced by conventional deasphalting agents which deasphalting mixture is used to dewax the deasphalting hydrocarbon mix-

2

ture. It is also an object of the present invention to provide a deasphalting mixture which retains in the raffinate the fluid constituents of a hydrocarbon mixture which are of high viscosity and which are normally discarded with the asphalt. The present invention also provides for a method of deasphalting and dewaxing hydrocarbon mixtures employing a mixture of agents which can effect economies in the dewaxing operation through vaporization of a portion of the diluent of the diluent-raffinate phase of the deasphalting operation to chill the raffinate prior to dewaxing. Other objects and advantages are contemplated as will be apparent from the following description.

In general, the use of a mixture of the same substances as a deasphalting mixture and a dewaxing mixture comprises deasphalting a hydrocarbon mixture containing asphaltic materials with a conventional deasphalting agent admixed with a small but effective amount of a modifier which is an organic carbonate. The term "organic carbonate" includes the carbonates of the monovalent residues of aliphatic, cycloaliphatic or aromatic hydrocarbons or heterocyclic compounds such as cyclohexyl carbonate, ethyl carbonate, phenyl carbonate and thiethyl carbonate. Preferred among the conventional deasphalting agents are the liquefied normally gaseous hydrocarbons, such as propane and preferred, for practical reasons at present, among the organic carbonates is diethyl carbonate.

The hydrocarbon mixture to be deasphalting and dewaxed is mixed with the deasphalting mixture of deasphalting agent and modifier and the asphaltic material precipitated. The asphaltic material is then washed with fresh deasphalting agent and/or modifier, the washings combined with the raffinate, the raffinate chilled by vaporization of the excess of the volatile component of the deasphalting mixture or by other means to a temperature at which dewaxing is achieved and the wax washed with fresh dewaxing mixture.

In the deasphalting operation the asphaltic waxy mixture of hydrocarbons is diluted with from 1 to 15 parts by volume of deasphalting mixture per volume of hydrocarbon mixture. Preferably, the modifier is used in amounts up to about 20 volume per cent of the deasphalting mixture. Greater amounts of modifier can be used but at the cost of diminishing returns. Preferably the organic carbonate, for example, ethyl carbonate, is used in the range of 1 to 12.0 volume per cent of the deasphalting mixture. It

is also preferred to use deasphalting mixture to oil ratios of about 3:1 to about 10:1 by volume. For satisfactory results in the dewaxing operation when using propanediethyl carbonate mixture as a dewaxing mixture, the composition of the deasphalting mixture must be changed from 80 to 99 per cent liquefied normally gaseous hydrocarbon, 20 to 1.0 per cent organic carbonate to a dewaxing composition of about 60-70 volume per cent of organic carbonate and 40-30 volume per cent of liquefied normally gaseous hydrocarbon. The satisfactory range of dewaxing mixture-raffinate ratios is from 8:1 to 0.2:1 with a ratio of 3 volumes of dewaxing mixture to 1 of raffinate or deasphalting oil preferred. An effective method of achieving this change in the composition of the deasphalting mixture for use as a dewaxing mixture is removal of the propane by evaporation. This not only brings about the required change in the ratio of propane to organic carbonate but also brings about the required chilling of the raffinate to the desired dewaxing temperature. After separation of the dewaxing mixture from the dewaxed, deasphalting raffinate, the dewaxing mixture is converted to a deasphalting mixture by adding back an amount of propane equivalent to that evaporated from the raffinate after deasphalting or sufficient to provide a deasphalting mixture. When desirable or necessary, the content of organic carbonate-deasphalting agent mixture can be adjusted before dewaxing by the addition of organic carbonate or by depropanizing and adding organic carbonate.

Illustrative of the use of the novel deasphalting-dewaxing mixtures are the following non-limiting examples.

EXAMPLE I

"A" (deasphalting)

A residual oil having a Saybolt Universal Viscosity of 1058 seconds at 210° F. was treated in a tower type deasphalting unit employing 10.5 volumes of deasphalting mixture to one volume of oil. The deasphalting mixture comprised 95.2 volume per cent propane and 4.8 volume per cent diethyl carbonate. In other words, 10 volumes of propane and .5 volume of diethyl carbonate were used for each volume of oil. The tower was operated with a temperature of 180° F. at the top of the tower and a temperature of 120° F. at the bottom of the tower. A yield of 69.2 volume per cent of oil having a Saybolt Universal Viscosity of 165 seconds at 210° F., a color of 375 Lovibond in a 1/4 inch cell and a 1.8 weight per cent carbon residue was obtained.

propane. The deasphalting oil (raffinate)-dewaxing mixture (adjusted deasphalting mixture) was chilled to a temperature of 1° F. and the precipitated wax separated. The precipitated wax was washed with about 2 volumes of dewaxing mixture at the temperature of separation. (As is well known to those skilled in the art, the wax can be separated by filtration, centrifugation, etc.) The washed wax amounted to 9.5 volume per cent of the deasphalting raffinate and had a needle penetration of 50. The dewaxed, deasphalting oil after steam stripping had an A. S. T. M. pour point of 10° F., a viscosity of 190 seconds S. U. V. at 210° F., and a viscosity index of 72.

15

"C"

Illustrative of the fact that heavier hydrocarbons than propane can be used is the following in which the deasphalting raffinate obtained according to the description given hereinbefore in IA was dewaxed with a mixture of petroleum ether (pentane-hexane mixture) and diethyl carbonate.

A portion of the deasphalting oil obtained in IA was freed of deasphalting mixture and refluxed with 3 volumes of a dewaxing mixture for each volume of oil. The dewaxing mixture comprised about 65 volume per cent diethyl carbonate and about 35 volume per cent petroleum ether (pentane-hexane mixture). The mixture of deasphalting oil and dewaxing mixture was chilled to 1° F. and the wax separated. The separated wax was washed with about two volumes of dewaxing mixture at the temperature of wax separation. A 10.7 volume per cent yield of wax was obtained. After steam stripping, the dewaxed, deasphalting oil had an A. S. T. M. pour point of 0° F., a viscosity at 210° F. of 193 seconds S. U. V. and a viscosity index of 72.

40

"D"

For purposes of comparison, a portion of the deasphalting oil obtained as described hereinbefore in IA was freed of deasphalting mixture and refluxed with a conventional dewaxing mixture comprising about 54 volume per cent of benzol, about 6 volume per cent of toluol and about 40 volume per cent of methyl-ethyl ketone. Thereafter, the mixture was chilled to 0° F., the wax separated and washed with about two volumes of B-T-M. E. K. dewaxing mixture. A 9.7 volume per cent of wax having a 66 needle penetration was obtained. After steam stripping, the dewaxed, deasphalting oil had an A. S. T. M. pour point of 5° F., a viscosity at 210° F. of 193 seconds S. U. V. and a viscosity index of 70.

For ease of comparison the foregoing results are tabulated as follows:

Dewaxing Mixture	3 vol.: 1 vol. oil 65 vol. % $(C_2H_5O)_2CO$ 35 vol. % propane	3 vol.: 1 vol. oil 65 vol. % $(C_2H_5O)_2CO$ 35 vol. % pet. ether	3 vol.: 1 vol. oil 54 vol. % benzol 6 vol. % toluol 40 vol. % M. E. K.

"B" (dewaxing)

70

EXAMPLE II

"A"

The composition of a portion of the mixture of raffinate and deasphalting mixture was adjusted to provide a diluent to oil ratio of 3:1 by volume and a diluent composition of about 64 volume per cent of diethyl carbonate and 36 volume per cent

75 was refluxed with about 3 volumes of dewaxing

5

mixture comprising about 65 volume per cent of diethyl carbonate and about 35 volume per cent of intermediate naphtha (predominantly paraffinic) having a boiling range of about 200° F. to about 300° F. The mixture was chilled to 0° F. and the wax separated. The separated wax was washed at the temperature of separation with two volumes of dewaxing mixture. A 12.1 volume per cent yield of wax was obtained. The dewaxed, deasphalting, refined oil, after steam stripping, had an A. S. T. M. pour point of 20° F., a viscosity at 210° F. of 85.9 seconds (S. U. V.) and a viscosity index of 96.

"B"

A portion of the same oil was refluxed with three volumes of dewaxing solvent containing 57 volume per cent benzol, 3 volume per cent toluol and 40 volume per cent methyl-ethyl ketone. The oil-solvent mixture was then chilled to 0° F., the wax separated and washed at the temperature of separation with two volumes of said solvent. A 11.9 volume per cent yield of wax was obtained. The dewaxed oil, after steam stripping had an A. S. T. M. pour point of 20° F., a viscosity at 210° F. of 92.5 seconds (S. U. V.) and a viscosity index of 96.

EXAMPLE III

"A"

A deasphalting, solvent refined residual stock having a viscosity at 210° F. of 84.6 seconds (S. U. V.) was refluxed with three volumes of dewaxing mixture comprising 66.6 volume per cent diethyl carbonate and 33.4 volume per cent propane. The oil-dewaxing mixture was chilled to minus 1° F., the wax separated and the wax washed at the temperature of separation with two volumes of dewaxing mixture. A 13.8 volume per cent yield of wax was obtained having a needle penetration of 35. After steam stripping, the dewaxed oil had an A. S. T. M. pour point of 15° F., a viscosity at 210° F. of 88.6 seconds (S. U. V.) and a viscosity index of 97.

"B"

A portion of the deasphalting, solvent refined,

"C"

A portion of the deasphalting, solvent refined, residual oil used in IIIA and IIIB was refluxed with three volumes of liquid propane at super-atmospheric pressure. The oil-propane mixture was chilled to minus 18° F. and the wax separated. The wax was washed with two volumes of liquid propane at the temperature of separation. A 27.7 volume per cent yield of wax having a needle penetration of 145 was obtained. The steam stripped dewaxed oil had an A. S. T. M. pour point of 20° F., a viscosity at 210° F., of 88.5 seconds (S. U. V.) and a viscosity index of 96.

15

"D"

A fourth portion of the deasphalting, solvent refined residual oil used in IIIA, IIIB and IIIC was refluxed with three volumes of conventional dewaxing solvent comprising 54 volume per cent benzol, 6 volume per cent toluol and 40 volume per cent methyl-ethyl ketone (M. E. K.). The oil-solvent mixture was chilled to minus 1° F. and the wax separated. The wax was washed at the temperature of separation with two volumes of the solvent. A 13.6 volume per cent yield of wax having a needle penetration of 60 was obtained. The steam-stripped dewaxed oil had an A. S. T. M. pour point of 15° F., a viscosity at 210° F. of 89 seconds (S. U. V.) and a viscosity index of 95.

30

"E"

A portion of the deasphalting, solvent refined residual oil used in III A, B, C and D was refluxed with three volumes of dewaxing mixture comprising 65 volume per cent diethyl carbonate [$(C_2H_5O)_2CO$] and 35 volume per cent propane. The oil-dewaxing mixture was chilled to minus 21° F. and the wax separated. The wax was washed at the temperature of separation with two volumes of dewaxing mixture. A 19.8 volume per cent yield of wax having a needle penetration of 56 was obtained. The steam stripped dewaxed oil had an A. S. T. M. pour point of 5° F., a viscosity at 210° F. of 88.9 seconds (S. U. V.) and a viscosity index of 93. These data are compared in Table II:

TABLE II

residual oil used in IIIA was refluxed at super-atmospheric pressure with three volumes of liquid propane. The oil-propane mixture was chilled to minus 1° F. and the wax separated. The wax was washed at the temperature of separation with two volumes of liquid propane. A 14.9 volume per cent yield of wax having a needle penetration of 60 was obtained. After steam stripping the dewaxed oil had an A. S. T. M. pour point of 30° F., a viscosity at 210° F. of 88.4 seconds (S. U. V.) and a viscosity index of 97.

65 Those skilled in the art will recognize the advantages attendant upon the use as a dewaxing mixture of liquefied normally gaseous hydrocarbons, such as propane and organic carbonates. When propane alone is used and a dewaxed oil 70 having an A. S. T. M. pour point of about 20° F. is the desideratum, the oil-propane mixture must be chilled to minus 18° F. On the other hand, employing propane and an organic carbonate, such as diethyl carbonate, it is only necessary to chill 75 the oil-dewaxing mixture to about minus 1° F.

(IIIC vs. IID). On the other hand, if the oil-propane-organic carbonate mixture is chilled to minus 21° F. (approximately the temperature of wax separation with propane to provide a dewaxed oil of A. S. T. M. pour point of 20° F.), the dewaxed oil has an A. S. T. M. pour point of 5° F. In other words, the use of organic carbonates in conjunction with liquefied normally gaseous hydrocarbons makes it possible to obtain improved deasphalting and improved dewaxing. Furthermore, to obtain comparable dewaxing results at comparable temperatures it is necessary to use a different dewaxing solvent when propane or the like has been used as a deasphalting diluent. That is to say, in order to obtain a deasphalting, dewaxed, solvent refined oil having an A. S. T. M. pour point of 15° F. when using propane and comparable dewaxing temperatures it is necessary to use benzol-toluol-M. E. K. as the dewaxing solvent; that is to say, one solvent or diluent for deasphalting and another totally different solvent or diluent for dewaxing. On the other hand, employing propane and an organic carbonate as a deasphalting agent it is only necessary to adjust the carbonate concentration and the deasphalting mixture is ready for use as a dewaxing mixture.

As used hereinbefore and hereinafter in the claims, the term deasphalting agent includes within its scope those hydrocarbons, mixtures of hydrocarbons, organic compounds and the like which are known to those skilled in the art to function as diluents or solvents for the non-asphaltic components of petroleum and the term deasphalting mixture includes within its scope the mixture of one or more of said deasphalting agents and one or more of the novel modifiers enumerated hereinbefore conforming to the general formula (RO)₂CO where R is the monovalent residue of an aliphatic, cycloaliphatic or aromatic hydrocarbon or a heterocyclic compound.

I claim:

1. A method of deasphalting and dewaxing hydrocarbon mixtures which comprises mixing a hydrocarbon mixture containing asphaltic materials and wax with a deasphalting mixture comprising in excess of 75 volume per cent liquefied normally gaseous hydrocarbons and the balance an organic carbonate, separating asphalt from said mixture, adjusting the composition of the mixture of deasphalting oil and deasphalting mixture to raise the ratio of organic carbonate to liquefied normally gaseous hydrocarbon to about 3:1 to 1:3, and separating wax.

2. A method of deasphalting and dewaxing hydrocarbon mixtures which comprises mixing a hydrocarbon mixture containing asphaltic materials and waxy materials with 1 to 15 volumes of deasphalting mixture comprising liquefied normally gaseous hydrocarbon and about 1.0 to about 20 volume per cent of an organic carbonate, separating asphaltic material and recovering a mixture of deasphalting oil and said deasphalting mixture, adjusting the concentration of liquefied normally gaseous hydrocarbon and organic carbonate in said recovered mixture to provide about 0.2 to about 8 volumes of liquefied normally gaseous hydrocarbon and organic carbonate per volume of deasphalting oil, said liquefied normally gaseous hydrocarbon being present in a concentration of about 25 to 75 volume per cent and the organic carbonate being present in a concentration of about 75 to 25 volume per cent of the mixture exclusive of the deasphalting oil, and separating waxy material.

3. A method of deasphalting and dewaxing petroleum oils which comprises mixing one volume of petroleum oil containing asphaltic and waxy materials with 1 to 15 volumes of a deasphalting mixture comprising about 80 to about 99 volume per cent liquefied normally gaseous hydrocarbon and about 20 to about 1 volume per cent of organic carbonate to obtain a mixture, separating asphaltic material to leave a mixture of deasphalting oil and deasphalting mixture, adjusting the composition of said deasphalting mixture to provide a mixture of liquefied normally gaseous hydrocarbon and organic carbonate comprising about 25 to about 75 volume per cent of liquefied normally gaseous hydrocarbon and about 75 to about 25 volume per cent organic carbonate to provide a dewaxing mixture, chilling said deasphalting oil in admixture with said dewaxing mixture to a temperature at which wax separates, separating said wax to leave a mixture of deasphalting and dewaxed oil and dewaxing mixture.

4. A method of deasphalting and dewaxing petroleum oils which comprises mixing one volume of petroleum oil containing asphaltic and waxy materials with 1 to 15 volumes of a deasphalting mixture comprising about 80 to about 99 volume per cent liquefied normally gaseous hydrocarbon and about 20 to about 1 volume per cent organic carbonate to obtain a mixture, separating said asphaltic material to leave a mixture of deasphalting oil and deasphalting mixture, adjusting the composition of said deasphalting mixture in situ to provide a dewaxing mixture comprising about 25 to about 75 volume per cent of liquefied normally gaseous hydrocarbon and about 75 to about 25 volume per cent organic carbonate, cooling the mixture of deasphalting oil and dewaxing mixture to precipitate waxy material, separating said waxy material to leave a mixture of deasphalting and dewaxed petroleum oil and dewaxing mixture, separating said dewaxing mixture from deasphalting and dewaxed oil, adjusting the composition of said dewaxing mixture to provide a deasphalting mixture, and deasphalting a mixture of hydrocarbons containing asphaltic material.

5. A method of deasphalting and dewaxing petroleum oils which comprises mixing petroleum oil containing asphaltic material and waxy material with a deasphalting mixture comprising about 80 to 99 volume per cent liquefied normally gaseous hydrocarbon and about 20 to about 1 volume per cent organic carbonate in the ratio of one volume of oil to 1 to 15 volumes of deasphalting mixture, separating a mixture of deasphalting oil and deasphalting mixture from precipitated asphaltic material, adjusting the composition of said mixture of deasphalting oil and deasphalting mixture to provide a mixture of deasphalting oil and adjusted deasphalting mixture, hereafter called dewaxing mixture, containing deasphalting oil and dewaxing mixture in the ratio of about 1 to 0.2 to 1 to 8, said dewaxing mixture comprising about 25 to about 75 volume per cent organic carbonate and about 75 to about 25 volume per cent liquefied normally gaseous hydrocarbon, cooling said mixture of deasphalting oil and dewaxing mixture to a temperature at which waxy material solidifies, separating a mixture of dewaxed, deasphalting oil and dewaxing mixture from waxy material, separating said dewaxing mixture from said deasphalting and dewaxed oil, and adjusting the composition of said dewaxing mixture to provide a deasphalting mixture.

6. The method of deasphalting and dewaxing hydrocarbon mixtures containing asphaltic ma-

terial and waxy material as described and set forth in claim 1 in which the organic carbonate is diethyl carbonate.

7. The method of deasphalting and dewaxing petroleum oil as described and set forth in claim 3 in which the organic carbonate is diethyl carbonate.

8. The method of deasphalting and dewaxing petroleum oil as described and set forth in claim 5 in which the organic carbonate is diethyl carbonate.

9. The method of deasphalting and dewaxing a residual petroleum oil which comprises mixing a residual petroleum oil and a deasphalting mixture comprising about 92 to about 98.5 volume per cent propane and about 8 to about 1.5 volume per cent of diethyl carbonate in the ratio of 1 volume of residual oil to about 2 to about 10 volumes of deasphalting mixture at a temperature at which asphaltic material is substantially immiscible with said mixture of residual oil and deasphalting mixture, separating a mixture of deasphaled residual oil and deasphalting mixture from said immiscible asphaltic material, adjusting the composition of said latter mixture in situ to provide an adjusted mixture containing deasphaled oil and dewaxing mixture in the ratio of 1 to about 0.2 to about 8, said dewaxing mixture comprising about 60 to about 70 volume per cent diethyl carbonate and about 40 to about 30 volume per cent propane, cooling said adjusted mixture to a temperature at which waxy material solidifies, and separating deasphaled and dewaxed oil from waxy material.

10. The method of deasphalting and dewaxing residual petroleum oil as described and set forth in claim 9 in which the composition of the dewaxing mixture is adjusted to provide a deasphalting mixture after separation from the dewaxed, deasphaled oil.

11. The method of deasphalting and dewaxing hydrocarbon mixtures which comprises mixing a hydrocarbon mixture containing asphaltic materials and waxy materials with a deasphalting mixture comprising a deasphalting agent and an organic carbonate, separating asphaltic material from a residual mixture of deasphaled hydrocarbons and deasphalting mixture, adjusting the concentration of deasphalting agent and organic carbonate in said residual mixture to provide a greater concentration of organic carbonate in

said residual mixture effective, in conjunction with the reduced concentration of deasphalting agent, as a dewaxing mixture, chilling said residual mixture having adjusted concentration of organic carbonate and deasphalting agent to a temperature at which waxy material present therein solidifies, and separating said waxy material.

12. The method of deasphalting and dewaxing 10 hydrocarbon mixtures which comprises mixing a hydrocarbon mixture containing asphaltic materials and waxy materials with a deasphalting mixture comprising a deasphalting agent and an organic carbonate, separating asphaltic material from a residual mixture of deasphaled hydrocarbons and deasphalting mixture, adjusting the concentration of deasphalting agent and organic carbonate in said residual mixture to provide a greater concentration of organic carbonate in 15 said residual mixture effective, in conjunction with the reduced concentration of deasphalting agent, as a dewaxing mixture, chilling said residual mixture having adjusted concentration of organic carbonate and deasphalting agent to a temperature at which waxy material present therein solidifies, separating said waxy material from a second residual mixture containing deasphaled hydrocarbons and dewaxing mixture, separating dewaxing mixture from said second residual mixture, treating said separated dewaxing mixture to increase the concentration of deasphalting agent to provide a regenerated deasphalting mixture; and deasphalting another 20 quantity of hydrocarbons.
